UNITED STATES PATENT OFFICE.

EDMUND S. CHURCH, OF CHICAGO, ILLINOIS, ASSIGNOR TO AUTOMATIC CARBURETOR CO., OF CHICAGO, ILLINOIS, A CORPORATION OF ILLINOIS.

CURTAIN-FASTENER.

1,285,039.

Specification of Letters Patent. Patented Nov. 19, 1918.

Application filed March 10, 1917. Serial No. 153,818.

To all whom it may concern:

Be it known that I, EDMUND S. CHURCH, a citizen of the United States, and a resident of Chicago, in the county of Cook and State 5 of Illinois, have invented certain new and useful Improvements in Curtain-Fasteners, of which the following is a full, clear, and exact description.

The invention relates to curtain fasteners, 10 such as are used on automobiles.

The object of the invention is to provide an improved fastener whereby the curtain will be positively locked on the stud and which permits convenient release of the curtain 15 by finger pressure applied in removing the curtain from the fastener.

A further object of the invention is to provide an improved curtain fastener which is simple in construction, is adapted to 20 securely hold the curtain, and can be produced at a low cost.

The invention consists in the several novel features hereinafter set forth and more particularly defined by claims at the conclusion 25 hereof.

In the drawings: Figure 1 is a side elevation of the improved fastener, a support and curtain being shown in section, and showing the manner of manipulating the fastener to release the curtain. Fig. 2 is a face view. Fig. 3 is a face view of the hollow stud and its base. Fig. 4 is an inner face view of the curtain showing the washer secured thereto and adapted to fit around 30 the hollow stud. Fig. 5 is a horizontal section on an enlarged scale. Fig. 6 is a section taken on line 6—6 of Fig. 5.

The invention is shown as applied to a suitable support 7 to hold a curtain 8. The 40 improved fastener comprises a hollow stud 9 having a rounded or convex outer end 10 and formed with an integral hollow base 11 provided with holes for screws 12 whereby the stud may be rigidly secured to the support 7. The stud 9 and base 11 are preferably formed of sheet metal and a back-plate 14 is secured in the hollow base 11 to close the back of the latter and to provide a support for the latch as hereinafter set 45 forth. Plate 14 fits into the base 11 and is rigidly secured therein by annular flanges 15 which extend around the screws 12 and backwardly from the front-wall of the base and have their ends riveted to the back-plate 50 14 to fix said plate in the base.

A latch 20 is pivotally connected by a pin 21 to an ear or lug 22 formed on the back-plate 14. This ear or lug is struck up from the back plate which is formed of sheet metal. Latch 20 is rigid in itself and disposed in the hollow stud 9 and is extended through a transverse slot 23 formed in the curved terminal 10 of the hollow stud and is formed with a stop-portion 24 normally disposed to project outwardly or upwardly 60 from the periphery of the stud to prevent the curtain from being withdrawn. A spring 25 is coiled around pin 21 and interposed between the latch and the back plate 14 to normally hold the latch in operative 65 position. The outer edge of the latch is serrated or ribbed, as at 26, so that it can be easily gripped or moved by finger pressure applied to overcome the force of spring 25 and it is also formed so that when the latch 70 is shifted inwardly, the stop-portion 24 will be disposed within the stud or so that it will not project beyond its periphery and will leave the stud clear for withdrawal of the 75 socket on the curtain. The curtain 7 is 80 formed with an opening 28 for the stud to pass therethrough and this opening is usually reinforced by washers 29 and 30 which are clamped to the curtain by tongues 32 on washer 29 which extend through holes 85 in the washers and are clenched on the inner side of the inner washer 30. These washers are perforated so they will pass around and form a metallic socket for the hollow stud.

In operation, the projecting portion 24 90 of latch 20 will act to positively prevent the withdrawal of the curtain from the stud, because outward pressure of the curtain will not tend to move the latch against the force of the spring. To release the curtain, it is 95 only necessary to shift the portion projecting from the slot 23 transversely in slot 23 so that the opening in the washers on the curtain will clear the locking portion 24. This can be conveniently done by the thumb of 100 the hand applied at the same time that the curtain is grasped for withdrawal as shown in Fig. 1. By thumb pressure on the latch, the curtain will be released so that it can be easily withdrawn from the stud. To place 105 the curtain on the stud, it is only necessary to force it over the stud. The washers on the curtain, in being forced backwardly, will force the latch transversely against the force of the spring so the curtain and washers can 110

pass onto the stud, and as soon as the curtain has passed to the rear of the locking portion 24 of the latch, the spring will force the latch into operative position and the curtain will be securely held on the stud.

The invention exemplifies a curtain fastener in which a latch mounted in a hollow stud and movable transversely in a slot in the end of the stud, will serve to hold the curtain and which can be easily manipulated to release the curtain. Also one, in which the resiliency of a latch is not relied upon to hold the curtain, because the outward pressure of the curtain against the locking portion of the latch has no tendency to move the latch transversely to the stud. The device is formed mainly of sheet metal parts which can be produced at a low cost and is efficient in operation.

20 The invention is not to be understood as restricted to the details set forth, since these may be modified within the scope of the appended claims, without departing from the spirit and scope of the invention.

25 Having thus described the invention, what I claim as new and desire to secure by Letters Patent, is:

1. In a curtain fastener, the combination of a hollow stud having an integral, thin, 30 peripheral and end wall provided with means whereby it may be secured to a support and having a slot in its outer end, a movable latch having a portion projecting through said slot and from the periphery of 35 the stud to hold a curtain on the stud the latch being movable in the slot to release the curtain, and means in the hollow stud to sustain the inner end of the latch.

40 2. In a curtain fastener, the combination of a hollow stud comprising an annular peripheral and end wall, provided with

means whereby it may be secured to a support and having a transverse slot at its outer end and a latch having its inner end sustained in the hollow stud and its outer end 45 projecting through said slot and from the stud near the outer end thereof, to hold a part on the stud, the outer end of the latch being movable in the slot to release said part.

3. In a curtain fastener, the combination 50 of a hollow stud provided with means whereby it may be secured to a support and having a transverse slot at its outer end, and a latch having its inner end sustained in the hollow stud and having its outer end 55 conforming generally to the shape of the outer end of the stud and provided with a portion extending through the slot and projecting from the stud to hold a curtain on the stud, the outer end of the latch being 60 movable in the slot to release the curtain.

4. The combination of a hollow stud having means whereby it may be secured to a support, and having a transverse slot at its outer end, a latch in the stud and having a portion projecting through said slot to hold a curtain on the stud and whereby the latch may be shifted to release the curtain, and a 65 back plate secured to the back of the stud and having means for supporting said latch. 70

5. The combination of a hollow stud provided with a base having means whereby it may be secured to a support, and having a transverse slot at its outer end, a latch in the stud and having a portion projecting through said slot to hold a curtain on the stud and whereby the latch may be shifted to release the curtain, and a back-plate secured to the back of the base and having 75 means for supporting said latch.

EDMUND S. CHURCH.
